VALVE

Filed Sept. 28, 1931

FIG. 2.

INVENTOR
LEWIS L. DOLLINGER
By
Lewis Dollinger
ATTORNEY

UNITED STATES PATENT OFFICE

LEWIS L. DOLLINGER, OF ROCHESTER, NEW YORK

VALVE

Application filed September 28, 1931. Serial No. 565,521.

This invention relates to flushing tanks for water closets and has for its object to provide a drainage valve for such a tank which may be operated to drain all or only part of the tank for the purpose of flushing the water closet.

Another object of this invention is to so construct the valve and its operating mechanism that it may be used in practically any water closet tank in place of the now standard drainage valve.

These and other objects and attendant advantages will become more readily apparent from a detailed description of the invention which follows, reference being had to the accompanying drawing in which

Figure 1 shows a sectional view of a flushing tank equipped with my improved drainage valve.

Figure 2 is a detail sectional view of a modified form of one of the valves.

The valve mechanism and inlet for filling the flushing tank form no part of my invention as any of the usual types of filling mechanisms may be used in connection with my drainage valve. The filling mechanism of the tank is therefore not illustrated and described.

In all water closets the water tank is completely emptied every time the closet is flushed. This is a waste of water whenever the closet is used as a urinal, because in that case only about one-third of the volume of water in the tank is necessary to sanitarily flush the closet. Two thirds of the volume of water of the tank is thus wasted. The increase in the water consumption in most of the growing cities has in many cases taxed the water resources to the limit and means are constantly sought to either increase the water supply or effect a saving of the existing water supply. It is believed that with the use of my present invention many gallons of water would be saved in each household without in any way jeopardizing the sanitary function of the water closet.

As illustrated in the accompanying drawing the saving of water is effected by the use of a double drain valve which is used in place of the single drain valve now universally used

in combinations with all water closets. This double drain valve is operated by the same operating mechanism as that used for operating a single drain valve and is manipulated by a suitable turning handle 1 located on the outside of the tank. The motion of this handle is transmitted to a lever arm 2 pivoted on the inside of the tank so that this lever can be raised at will. By means of this turning handle 1 and lever 2 the double drain valve is operated to either drain all or but a part of the tank 3 for flushing purposes.

The double drain valve comprises the hollow rubber valve member 4 which is suitably attached to the open bottom of the cylindrical chamber 5. In the cylindrical wall of this chamber are provided the openings 6, 6 which permit water to enter the chamber 5 and hollow valve member and pass out thru the opening 7 in the center of the bottom of the valve member. The valve member 4 is adapted to be seated on the valve seat 8 which surrounds the outlet 9 leading to the water closet 10. In this way water passing thru the valve member 4 while it is seated on the valve seat 8 will flush the closet the same way as water entering directly into the outlet 9 on the raising of the valve member 4 from the valve seat 8.

The water entering the openings 6, 6 in the cylindrical wall of the chamber 5 of the valve member is controlled by a sleeve valve 11 which telescopes over the cylindrical chamber 5 and is provided at the open end with a flange 12 which is adapted to seat itself on the annular shoulder 14 of the valve member 4 to provide a seal between the gasket and shoulder to prevent water from entering the chamber 5 while the sleeve valve is held telescoped over it.

Suitably attached to the upper end of the sleeve valve 11 is a hollow and externally threaded stem 15. This stem is closed at the top and has the float member 16 threaded thereon so that it can be vertically adjusted on the stem for a purpose that will presently appear. A nut 17, threaded to the stem 15, serves as a shoulder which is engaged by the link 18 carried by the lever arm 2 when the

latter is raised on the operation of the turning handle 1. In this way the raising of the lever arm 2 by the handle 1 effects first a raising of the stem 15 with its float 16 and sleeve valve 11. This unseats the flange 12 from the shoulder 14 of the valve member 4 and permits the water from the tank to enter the openings 6, 6 in the side of the cylindrical valve chamber 5 and pass thru the valve member 4 into the outlet 9. For this operation of the sleeve valve 11 the valve handle is only partially operated and as soon as the valve 11 is open it is held open by the action of the float member which keeps the sleeve valve elevated until the level of the water within the tank is lowered and the float has dropped to a point where the sleeve valve suspended from it again closes the openings 6, 6 in the valve chamber 5. By adjusting the float member 16 on the hollow stem 17 the water in the tank may thus be drained by the sleeve valve 11 to a predetermined level and in this way a portion of the water of the tank is allowed to enter the outlet 9 with practically the same pressure or head as water from the tank will enter the outlet 9 after the valve member 4 is unseated. The small portion of the water of the tank thus drained has practically the same cleansing or flushing force as the water of the tank when it is completely drained by the operation of the valve member 4 which will now be described.

The point at which the sleeve valve 11 operates to drain part of the water is readily noticeable in the operation of the handle 1 because as soon as the valve has been partially raised the resistance offered by the valve to a further movement of the handle is practically eliminated because after that the float continues to raise the valve until it is fully opened.

The movement of the sleeve valve 11 on the cylindrical valve chamber is limited by one or more stop pins 19 which are carried by the sleeve valve 11 and project into the guide slots 19A of the valve chamber 5. The sleeve valve 11 in its individual operation in this way can slide up on the valve chamber 5 only until the pin 19 engages the upper end of one of the guide slots 19A of the valve chamber 5. Raising the sleeve higher than this on a continued movement of the handle 1 and its lever 2 will therefore effect a raising of the valve chamber 5 and its valve member 4 and will unseat the valve member 4 from the seat 8 and allow the water from the tank to enter the outlet 9 without first passing thru the valve member 4.

As illustrated in Figure 1 the valve member 4 which is preferably made of rubber has incorporated therein a float chamber 22 which surrounds the hollow center portion thereof. This float chamber serves to give the valve member sufficient buoyancy to rise

with the valve chamber 5 after the valve member has been unseated as above described. In rising, the valve chamber telescopes into the sleeve valve 11 and remains therein until the falling water level in the tank has dropped to a point where the float chamber 22 of the valve member no longer can keep the valve member from seating itself on the seat 8. To guide and prevent the valve chamber 5 from binding within the sleeve valve 11, a guide pin 23 is provided on top of the valve chamber 5. This guide pin engages the hollow stem 15 of the sleeve valve and guides the pin in a straight line movement.

In Figure 2 I have illustrated the valve member 4 surrounded by a suitable casing 24 in which sufficient air will be trapped to provide the necessary buoyancy for the valve member without the aid of a float chamber such as is illustrated in Figure 1.

From the foregoing it will be apparent that I have devised a new and useful drainage mechanism for either partially or wholly emptying the contents of a tank with practically the same head or pressure, and while I have, in the present instance shown one embodiment thereof which will give in practice satisfactory results, it is to be understood that this embodiment is susceptible of modification in various particulars without departing from the spirit or scope of the invention or sacrificing any of its advantages.

I claim:

1. In a drainage valve mechanism for tanks having a single outlet the combination of a pair of valves, a float chamber cooperating with each of said valves to keep the valves afloat at different levels of the liquid in the tank and connecting means providing a lost motion in the movement of said valves.

2. In a drainage valve mechanism for tanks having a single outlet, the combination of a hollow valve for controlling the passage of liquid from the tank from the outside of said hollow valve into the outlet and a second valve carried by said first valve for controlling the passage of liquid thru said first valve into the outlet, a float carried by said second valve to hold it open on said first valve at a predetermined level of the liquid in the tank.

3. In a drainage valve mechanism for tanks having a single outlet for draining either all or part of the contents of the tank at the same static pressure the combination of a hollow valve member for closing said single outlet, said hollow valve member having an opening therein leading into said outlet from the inside of said valve member and having an opening leading into said valve member from said tank, a valve for controlling the passage of liquid into the inside of said valve member and movable means for operating said second valve to open the opening into said first named valve member during part

of its movement and operate said first named hollow valve member to open said outlet during the remainder of its movement.

4. In a drainage valve mechanism for tanks having a single outlet for draining either all or part of the contents of the tank at the same static pressure the combination of a hollow valve member for closing said single outlet, said hollow valve member having an opening therein leading into said outlet from the inside of said valve member and having an opening leading into said valve member from said tank, a valve for controlling the passage of liquid into the inside of said valve member and movable means for operating said second valve to open the opening into said first named valve member during part of its movement and operate said first named hollow valve member to open said outlet during the remainder of its movement, a float carried by said first named hollow valve member to keep said member afloat to one predetermined level of the liquid within the tank and a float carried by said second mentioned valve to keep said second mentioned valve afloat to another predetermined level of the liquid in the tank.

5. In a drainage valve mechanism for tanks having an outlet the combination of a hollow valve member having an opening in the bottom thereof, said hollow valve being adapted to close said outlet, a valve chamber provided on said hollow valve member having an opening in the side thereof and an air pocket formed above the opening, a second valve for opening and closing the opening in said valve chamber, and a float for controlling the closing of the opening by said second valve at a predetermined level of the liquid in said tank.

6. In a drainage valve mechanism for tanks having an outlet the combination of a hollow valve member having an opening in the bottom thereof, said hollow valve being adapted to close said outlet, a valve chamber provided on said hollow valve member having an opening in the side thereof and an air pocket formed above the opening, a second valve for opening and closing the opening in said valve chamber, and a float for controlling the closing of the opening by said second valve at a predetermined level of the liquid in said tank, and connecting means between said second named valve and said first named valve member to permit the operation of said first named valve member on the movement of said second named valve after the opening in said valve chamber has been opened thereby.

7. In a drainage valve mechanism for tanks having an outlet in the bottom thereof, the combination of a hollow valve member having an opening in the bottom thereof and being adapted to close said outlet with the opening leading into the outlet, a valve cham-

ber forming a continuation of said hollow valve member and having an opening in the side thereof, a sleeve valve mounted to slide on said valve chamber to open and close the opening in said valve chamber, a float carried by said sleeve valve and a float chamber on said hollow valve member, said float of said sleeve valve being at a different elevation from the float chamber of said hollow valve member, and means for connecting said sleeve valve with said hollow valve member with a lost motion in the movements between them.

8. A drainage valve comprising a valve member having a duct provided therethru and at the top and bottom a float chamber surrounding said duct, a valve seat supporting said valve member and surrounding the open bottom of said duct to provide a passage directly thru said duct with the valve member seated on said valve seat.

9. A drainage valve comprising a rubber member having a valve seat at the top and a valve seat at the bottom thereof with a duct leading thru said valve from one valve seat to the other.

10. A drainage valve comprising a rubber member having a duct leading thru the middle thereof, a valve seat on said rubber member at the inlet of said duct and a second valve seat at the outlet of said duct, and a float chamber associated with said rubber member.
